CLAIM

The ornamental design for an industrial traffic curtain strip, as shown and described.

DESCRIPTION

FIG. 1 is a front elevational view of an industrial traffic curtain strip showing my new design, shown as broken in order to indicate indeterminate length, the rear being identical in appearance;

FIG. 2 is a side elevational view thereof;

FIG. 3 is a top plan view;

FIG. 4 is a bottom plan view; and

FIG. 5 is an enlarged fragmentary side elevational view.
